UNITED STATES PATENT OFFICE.

JOHN F. GAIL, OF EVANSTON, ILLINOIS.

TUBE MACHINE.

Application filed November 8, 1920. Serial No. 422,419.

To all whom it may concern:

Be it known that I, JOHN F. GAIL, a citizen of the United States, residing at Evanston, in the county of Cook and State of Illinois, have invented certain new and useful Improvements in Tube Machines, of which the following is a specification.

My invention pertains to several important and valuable novel features of structure, resulting in improved modes of functioning, in machines for producing metal tubing or pipes having longitudinal welded joints or seams from sheets or strips of metal. Heretofore, appliances have been devised and used with a moderate degree of satisfaction, in which the flat metal strip or blank as it is fed along is shaped or bent up transversely to cylindrical form with its longitudinal edges in abutting relation, such lengthwise joint or seam being closed by welding, as by means of electric heating, during the travel of the stock through the apparatus.

Great difficulty has been experienced and much waste produced in attempting to use such machines for the production of tubes or pipes from relatively thin stock and the fused metal at the joint is not of such density and closeness of structure as is desirable. In endeavoring to make comparatively thin tubing in the known commercial machines, as soon as the metal along the joint becomes softened or fused, thus materially reducing the resistance offered by the tube to lateral contraction or collapse, there is great danger of the edge portions of the metal along the joint becoming overlapped, which, of course, is wholly undesirable, rendering the product unsuited for its intended use.

One object of the present invention is to provide a suitable machine which will efficiently and rapidly produce tubing from thin stock without danger of such edges becoming overlapped or displaced. I have found that this may be accomplished by so mounting and arranging the plurality of rollers or other members engaging and confining the tube at the point of heating and fusing that when the resistance which the tube opposes to them is reduced by the softening of the metal of the tube along the joint, by reason of the electrically generated heat, such rollers or other corresponding elements cannot approach one another, which if permitted would decrease the aperture or throat through which the tube is passing

causing the metal edges along the joint to override one another. The pressure imposed by such rollers on the tube or pipe is of considerable amount and to eliminate the possibility of their moving inwardly toward one another and thus contracting the throat or opening through the machine, when the mechanical resistance of the tube is diminished under the heat action, it is important that the mountings of such rollers be extremely rigid, free from play, and incapable of springing or yielding in the least degree. In fact, the play of the roller shafts in their bearings, even though the fits are as accurate and close as it is possible to make them, is neutralized to prevent the undesired action specified.

There is a tendency for the tubes or pipes produced by the machines now in common use to have the fused metal at the joints somewhat porous in character, and one object of this invention is to supply means for compressing or condensing such metal, at the same time reducing or eliminating entirely or in part the fin formed along the joints in pipes made in this manner.

A further purpose of the invention is the gradual heating of the metal of the blank to welding temperature rather than extremely suddenly producing heat sufficient to effect the fusing or welding operation.

Another feature of the invention is to so form or shape the edges of the metal at the joint that they will originally have a width of contact less than the thickness of the metal and preferably at the center of such metal thickness, whereby the welding will occur at such middle section and extend both inwardly and outwardly through the thickness of the metal as the latter becomes thoroughly heated. Thus a progressive welding effect is secured with added advantages with respect to the uniformity of the heating and of the density of the metal of the welded joint. An additional object of the invention is the employment of the electrical heating means to the best advantage. Without attempting to explain the scientific theory involved in my novel machine, I will merely state that it has been my experience in the employment of electric welding tube-making machines, that the nearer the secondary of the transformer or the transformer itself is to the tube acted upon by the current traversing such secondary circuit, the better the

result secured. An advantage is had apparently greater than that derived solely from the reduction of the resistance of the secondary circuit because of its shortened length. 5 Accordingly in my type of tube machine the transformer is brought as near as possible or feasible to the point where the welding operation takes place. As a suggestion why such an arrangement is a distinct electrical 10 advantage, but without confining or restricting myself to the theory advanced, I may say that possibly the more or less rapid travel of the tube of magnetic material in close association with the transformer may have some 15 direct or indirect reaction thereon.

To enable those skilled in this art to have a full and complete understanding of this invention both from structural and functional standpoints, and in order that such 20 persons may comprehend the manner in which the above-stated and other desirable objects are secured by the employment of this invention, I have illustrated a convenient embodiment of the invention, more or 25 less diagrammatically, in the accompanying drawings forming a part of this specification and to which reference should be had in connection with the following detailed description, like reference characters referring 30 to the same parts throughout the several views of such drawings.

In these drawings:

Figure 1 is a side elevation of the machine;

35 Figure 2 is a plan view of the same;

Figure 3 is a vertical section through the tube adjacent to the welding portion of the appliance with portions broken away;

40 Figure 4 is a plan view of the part of the machine shown in Figure 3 with the transformer, with the exception of its brushes, removed;

Figure 5 is an enlarged elevation of the portion of the machine shown in Figure 3;

45 Figure 6 is a vertical section through this portion of the apparatus near the tube traversing the machine;

Figure 7 is a vertical section on line 7-7 of Figure 3;

50 Figures 8, 9, and 10 illustrate different pairs of forming rolls;

Figure 11 is an enlarged cross-section through the tube and its contained water-cooled mandrel;

55 Figure 12 is a longitudinal section through the tube illustrating the manner of supporting the mandrel;

Figure 13 is a vertical section through the tube and mandrel;

60 Figure 14 depicts the rollers which form the edges of the metal strips; and

Figure 15 is a fragmentary view cross-wise the joint portion of the tube illustrating the same on an enlarged scale.

65 Referring to these drawings, particularly

Figures 1 and 2, it will be observed that at its right-hand part the appliance includes a series of pairs of concave tube-feeding rollers 20, 21 and 22 geared together at 23 as shown and driven or rotated from any suitable source of power not illustrated. Of course, any other appropriate means for advancing or feeding the tube or pipe, such as a draw-bench, may be employed instead of the particular structure depicted. All of the other rollers are free to turn or revolve on their own axes, or, in other words, they are not power driven.

The metal for the formation of the tube or pipe enters the machine in the form of a long, flat blank or ribbon 24 of the proper width and leaves the appliance as a completed tube or pipe 25 with a longitudinal welded joint.

Such metal strip first passes between a pair of forming rollers 26 and 27 which bend or shape the sheet-metal body transversely into the form 28 shown in cross-section in Figure 8. Such partially formed blank then passes between a second pair of rollers 29 and 30 which still further shape the metal, whereby it appears in cross-section as illustrated at 31 in Figure 9. Thereupon the strip or ribbon traverses the third pair of rollers 32 and 33 which deform it into the shape indicated at 34 in Figure 10.

So far as now described there is nothing new in the apparatus.

Instead of having both meeting edges of the metal at the longitudinal joint in the tube or pipe flat or with plane surfaces as has heretofore been customary, in the use of this machine one edge 35 of such partially formed tube 36 (Figures 11 and 15) is flat and radially disposed with reference to the center or axis of the tube, but the companion or abutting edge is oppositely beveled from its center line 37 providing two diverging or flaring surfaces 38 and 39. The purpose of this arrangement is to secure an initial small area of contact between the edges to effect efficient heating and to initiate the welding operation at the center of the edges from which it spreads or extends in opposite directions both inwardly and outwardly as the softening or fusing of the tube proceeds.

The next two pairs of rollers 40 and 41, Figures 1, 2 and 14, are alike and are designed to provide such surfaces on the edges of the sheet-metal forming the tube, and they are slightly inclined to the vertical to bring the joint in proper position with respect to the electrical contact rollers and other parts of the heating or welding apparatus.

The lower roller 41 of each pair has a face substantially semi-circular in cross-section adapted to engage the lower part of the exterior of the tube, whereas the upper companion or complementary roller is com-

posed of three elements or parts 42, 43 and 44 rigidly connected together in any approved manner. The section 42 has a transversely-curved operative face of substantially 90 degrees, whereas the corresponding face of the member 44 is somewhat less than 90 degrees, the intermediate disc 43 having a flat surface 45 on one side arranged radially with respect to the center of the 5 partially formed tube, a flat surface 46 on the other side of the disc parallel to the face 45, and another face 47 at an angle to the surface 46. By drawing the tube through these rollers and with its edges 10 against the opposite faces of the middle disc, the surface 45 assures the production on the corresponding edge of the metal of a radial, smooth, plane surface 35, while the surfaces 46 and 47 form the beveled 15 or flaring faces 38 and 39. The use of two pairs of such rollers 40 and 41 insures the production of the desired smooth surfaces on the edges of the metal ready for the fusing and welding operation.

20 Considering the electric heating and welding portion of the machine through which the metal strip or sheet now passes, it will be perceived that it includes a vertical concave roller 51 (Figure 3) and two, horizontal, concave rollers or discs 52 and 53, in the same plane, which may be located slightly in advance of the companion roller 51, unitedly forming a throat or opening 25 through which the tube is drawn and of less diameter than the space between the rollers 41, 42 and 44, whereby the strip in passing from the latter to the former group of 30 rollers has its previously separated longitudinal edges not only brought into line 35 contact but the metal on both sides of the lengthwise gap is pressed or forced inwardly toward the opposed or companion edge to produce the required upsetting to effect 40 the desired welding or union of the edges.

45 It is of great importance that these three revolvable rollers, of which the two horizontal ones 52 and 53 are electrical contact elements, suitably insulated, as may be required, designed to engage the tube on opposite sides of and close to its lengthwise joint, shall be very rigidly mounted so that 50 under no circumstances can they shift position or approach one another to reduce or decrease the normal space between them, 55 otherwise there would be great danger of the metal edges of the tube becoming overlapped, under the transverse pressure to which they are subjected, as soon as they become softened or partially fused, which 60 is especially likely to happen if tubes or pipes of very thin metal are being produced.

To this end the roller 51 which has a curved or grooved face encircling the lower half of the tube is revolvably mounted by 65 means of a suitable shaft 54 in aligned bear-

ings 55 and 56 on a very substantial frame 57 of which only a part is illustrated in the drawing. The two opposed, horizontal, slightly-separated rollers or discs 52 and 53 contact with the partially-finished tube on opposite sides of its lengthwise joint with a small space between their adjacent edges, the operative face of each of such rollers being curved on the same diameter or radius as the roller 51 so as to contact with slightly less than one-quarter of the transverse curvature of the tube. Thus it will be seen that, except for the slight space between the rollers 52 and 53, these three rollers entirely encircle the tube forming a 70 round opening of definite size through which the tube is drawn by the action of the feeding rollers 20, 21 and 22.

75 As has been indicated, all of these three rollers must be so firmly and rigidly mounted that under no circumstances shall they approach one another to reduce even in the smallest degree the space or opening between the rollers through which the tube 80 passes. With this in view, the horizontal roller 52 is mounted on a vertical shaft 58 revolvable in a bearing 59 in a block 60 adjustable horizontally lengthwise in a guideway 61 (Figure 7) provided in one 85 face of an upstanding portion 62 forming an integral part of the frame 57, the block 60 having a rib 63 accommodated and slideable in such guiding groove 61. As is illustrated, the block 60, if preferred, may have a sliding bearing on the flat horizontal face 90 95 100 105 110 115 120 125 130 of a portion of the frame in front of the part 62.

In similar manner, the complementary electrical contact roller or disc 53 is mounted on a vertical shaft 65 revolvable in a bearing 66 in a block 67 lengthwise or longitudinally adjustable toward and from the tube in the guide groove 61 in which its rib 63 fits and is adapted to slide, the block, similar to the block 60, resting on and having a sliding bearing on the face 64 of the main frame.

In order to firmly bind and clamp these two blocks 60 and 67 in their adjusted positions to the main frame so that under no circumstances could they shift position unintentionally, the machine is provided with a strap or bar 68 overlying the front faces of the two blocks and adapted to clamp the latter to the upright portion of the main frame by means of a plurality of bolts 69, 69 which when screwed up tightly render these adjustable blocks wholly immovable with respect to the substantial and solid main frame. Screw means may be employed if desired to secure accuracy and nicety of adjustment of these slideable blocks relatively to one another in their guiding grooves while the clamp bar 68 is loose, but inasmuch as such screw means are

well known in many lines of industry, for simplicity in illustration, no attempt has been made to show them in the drawings.

In actual practice the lengths of shafts 58 and 65 and their bearings 59 and 66 would preferably be much longer than shown in the drawings and even though such shafts fit their bearings as accurately as it is possible to make such constructions, 10 it is, nevertheless, desirable or necessary to eliminate the minute play between such shafts and their bearings, and accordingly the upper end of each of such shafts is accommodated in a bearing 70 in the end portion 15 of a member 71 adjustably slidable on the top of the corresponding block 60 or 67, as the case may be, by means of a pair of screws 72, 72 extended through threaded holes in lugs 73 upstanding from the blocks 20 60 and 67, and bearing at their ends against the outer faces of the elements 71, two of the latter being employed, one for each of the horizontal rollers. Block 71 is provided with a plurality of slots 74 extended vertically 25 therethrough each accommodating a clamping screw 75. Each block 71 is forced inwardly by its screws 72 whereby the outer half of its bearing 70 pressing against the corresponding portion of the upper part of 30 the shaft 58 or 65 forces such shaft inwardly toward the tube so that it will bear firmly against the inner half of the bearing 59 or 66, whereupon the screws 75 are tightened to hold the parts in this relation. 35 Therefore, under no circumstances can the roller 52 or 53 move inwardly in the slightest degree, nor can they spring outwardly, assuming that the blocks 60 and 67 are firmly clamped to the main support or 40 frame. Accordingly there is no danger of the throat or opening between the three rollers becoming contracted or reduced in size by reason of the rollers 52 and 53 approaching one another. Of course, there 45 are many other mechanical expedients for accomplishing this result, but I consider this portion of the invention of great importance because it renders possible the making of tubes or pipes of this character 50 out of relatively thin metal without danger of their longitudinal edges becoming overlapped or the tube otherwise deformed.

It is desirable also to prevent the rollers 52 and 53 changing relation to or approaching roller 51 and accordingly they are provided with interlocking or gauge means 55 performing this function. Wherefore, to accomplish this result and also to prevent short circuiting of the electrode or contact rollers 52 and 53 by the intermediate lower roller 51, each of the former is equipped with a thin layer or disc 151 of insulation material secured to its bottom face with its margin overlying and, if desired, in direct 60 contact with the adjacent side cylindrical 65

part of roller 51. Each element 52 or 53 beneath such insulation disc has a cylindrical metal disc 152 secured thereto with its circular margin above and bearing on the cylindrical periphery of a metal disc 153 70 fastened to or forming part of concave roller 51 and, if desired, its round edge may bear on the side face of roller 51 thus doubly assuring no possibility of rollers 52 and 53 approaching one another. 75

Obviously these several confining and restraining constructions prevent the possibility of contraction of the throat or opening formed unitedly by the rollers and through which the tube passes. 80

The electrical transformer 76 may be of any suitable construction, the one shown having a single turn secondary 77 in the bottom face of which are mounted a number of contact brushes 78 bearing on the top 85 surfaces of the horizontal contact rollers or discs 52 and 53, whereby to conduct the electric current through such rollers to the tube to be welded. 90

In advance of the points of contact of the rollers 52 and 53 with the tube, such secondary of the transformer is supplied with supplementary brushes 79, Figure 6, contacting directly with the tube on opposite sides of its lengthwise joint, so that the 95 metal of such joint is somewhat preliminarily heated before reaching the welding position, thus more or less gradually raising the heat of the metal to fusing temperature. 100

At the region of heating, the tube travels over a liquid-cooled mandrel 80 (Figures 11, 12 and 13), the cooling construction of which is shown more or less diagrammatically, which may or may not be of insulation material, supported by an arm 81 (Figure 12) 105 mounted on any appropriate part of the machine and extending into the interior of the tube through its joint opening in advance of the place of closing the latter. The top and side faces of such mandrel are rounded to 110 correspond to the interior curvature of the tube as shown in detail in Figure 11 and in the top face of the mandrel a cavity or depression 82 is provided in which is mounted a revoluble pressure or backing-up roller 83 115 of insulation material, glass for instance, located in register with the joint of the tube or pipe. In order to be able to adjust such mandrel or core and its roller up and down, that is toward and from the joint, a part at least of the bottom of the mandrel is beveled at 84, Figure 14, and, beneath this, and shaped on its under surface to conform to the corresponding curvature of the inner part of the lower portion of the tube, is a wedge-member 85 with a screw adjustment 86 on the mandrel, so that by shifting this underlying member lengthwise somewhat, the position of the mandrel proper and its roller may be varied as may be required from time 120 125 130

to time due to wear. The interior of the mandrel is supplied with flowing cooling liquid introduced in any appropriate manner as through one or more pipes 87. The mandrel proper may or may not contact with the inner surface of the tube, and in some cases it may be preferable to have the cooling liquid flow through the tube being formed rather than pass through the interior of the mandrel.

Above the joint of the tube and at the point of welding is a pressure-roller 88 of insulation material, and mounted in any approved manner preferably adjustable toward and from the joint, such roller at the same time acting as a spacer for the contact rollers 52 and 53. As illustrated, such roller is on the transformer and is adjustable up and down to vary its position with respect to the tube joint and the fin along the tube produced by the welding operation. If preferred, such roller may be mounted on a suitable bracket rather than on the transformer.

These two cooperating rollers 88 and 83 act to compress or condense the fused metal and prevent its becoming porous at the joint, at the same time reducing or eliminating entirely the fin along the joint brought about by the heating and welding operations.

The action of the machine occurs practically as follows: The long, flat, metal-blank, by means of the feeding-rollers 20, 21 and 22, is caused to pass between the successive pairs of forming rollers 26—27, 29—30, and 32—33 which gradually and progressively bend it up transversely, whereupon it passes to the two pairs of rollers 40 and 41 which shape its edges and bring them somewhat nearer together. Thereupon the tube travels through the throat or opening formed by the three rollers 51, 52 and 53 with the joint portion between the pressure-rollers 88 and 83. The electric current, traversing the rollers 52 and 53 and derived from the transformer, heats the metal of the joint progressively inwardly and outwardly from the center of its thickness to fusing or welding temperature, such parts having been initially or preliminarily heated somewhat by reason of the current passed through them by the advance brushes 79, and at the same time such softened or fused metal is condensed or compressed by the upper and lower presser-rollers, the inner one being adequately cooled as specified above. When the tube issues from the machine its lengthwise joint is not only closed and sealed but the metal thereof is of firm and dense texture and the external fin is either absent or relatively small in size.

Those skilled in this art will readily understand that this invention is susceptible of a variety of embodiments and is consequently not limited to the precise and exact details of structure herein presented because these

may be modified within comparatively wide limits without departure from the heart and essence of the invention and without the sacrifice of any of its substantial benefits and advantages.

For example, although a machine has been shown and described for forming round or cylindrical tubes, the invention is equally well adapted for manufacturing tubes or pipes of other shapes in cross-section, and notwithstanding the illustration and description of some of the rollers as single elements, they may be made of a plurality of parts or separate rollers.

I claim:

1. In a tube-welding machine of the character described, the combination of more than two rollers unitedly forming an opening through which the metal tube blank is adapted to pass, means to cause the blank to traverse said opening, supporting means for said rollers permitting them to revolve independently about their own axes, means to positively prevent said rollers from decreasing the desired size of said opening, two of such rollers being positioned to engage the tube on opposite sides of its longitudinal joint, and means to pass an electric heating current through such two rollers and the tube joint to weld the latter.

2. In a tube-welding machine of the character described, the combination of a pair of rollers adapted to engage the tube undergoing formation on opposite sides of its longitudinal joint, means to cause the metal tube blank to pass between said rollers, bearings for said rollers permitting them to revolve independently about their own axes, means to positively prevent said rollers from approaching one another beyond a predetermined point, and means to pass an electric heating current through said rollers and the tube joint.

3. In a tube-making machine of the character described, the combination of a roller positioned to engage the tube opposite its longitudinal joint, a pair of opposed rollers at substantially right angles to said first roller and positioned to engage the tube on opposite sides of the tube joint at points in substantially the same plane as the contact of the first roller with the tube, means to cause the tube blank to traverse the opening formed by said rollers, supporting means for said three rollers permitting them to revolve about their own axes, and means to positively prevent said rollers from decreasing the size of the opening formed by them and through which the tube blank passes.

4. In a tube-welding machine of the character described, the combination of a roller positioned to engage the tube opposite its longitudinal joint, a pair of opposed rollers at substantially right angles to said first

roller and positioned to engage the tube on opposite sides of said tube joint at points in substantially the same plane as the contact of the first roller with the tube, means to cause the tube blank to traverse the opening formed by said rollers, means to pass an electric heating current through said pair of rollers and the tube joint between them, and means to positively prevent such pair of rollers from decreasing the size of said opening.

5. In a tube-welding machine of the character described, the combination of a roller positioned to engage the portion of the tube opposite its longitudinal joint, a pair of opposed rollers at practically right angles to said first roller and positioned to engage the tube on opposite sides of said joint at points in substantially the same plane as the contact of the first roller with the tube, means to cause the tube blank to traverse the opening formed by said rollers, means to pass an electric heating current through said pair of rollers and the tube joint between them, and means to positively prevent all of said rollers from decreasing the size of said opening.

6. In a tube-welding machine of the character described, the combination of a roller having a concave face substantially semi-circular in cross-section and adapted to engage the half of the tube opposite its longitudinal joint, a pair of opposed rollers in substantially the same plane and at practically right angles to said first roller and having concave faces each of practically a quadrant of a circle in cross-section and positioned to engage the tube on opposite sides of said joint at points in substantially the same plane as the contact of the first roller with the tube, means to cause the tube blank to traverse the opening formed by said rollers, means to pass an electric heating current through said pair of rollers and the tube joint between them, and means to positively prevent all of said rollers from decreasing the size of said opening.

7. In a tube-welding machine of the character described, the combination of a pair of rollers in the same plane adapted to engage the tube on opposite sides of its longitudinal joint, shafts for said rollers, bearings for said shafts, means to maintain said shafts without play against the sides of such bearings nearest the tube, whereby the rollers are prevented from decreasing the distance between them, means to cause the tube blank to pass between said rollers, and means to pass an electric heating current through said rollers and the tube joint between them.

8. In a tube-welding machine of the character described, the combination of a roller positioned to engage the portion of the tube

opposite its longitudinal joint, a pair of opposed rollers at practically right angles to said first roller and positioned to engage the tube on opposite sides of said joint at points in substantially the same plane as the contact of the first roller with the tube, means to cause the tube blank to traverse the opening formed by said rollers, shafts for said pair of rollers, bearings for said shafts, means to maintain said shafts without play against the sides of such bearings nearest the tube, whereby to prevent decrease of the distance between said pair of rollers, and means to pass an electric heating current through said pair of rollers and the tube joint between them.

9. In a tube-forming machine of the character described, the combination of a roller adapted to engage the tube opposite its longitudinal joint, a pair of rollers adapted to engage the tube on opposite sides of said joint, overlapping discs interlocking said rollers together to prevent decrease in the size of the opening formed by the rollers, and means to cause the tube blank to traverse said opening.

10. In a tube-welding machine of the character described, the combination of a roller adapted to engage the tube opposite its longitudinal joint, a pair of contact rollers adapted to engage the tube on opposite sides of said joint, overlapping discs interlocking said rollers together to prevent decrease of the size of the opening formed by the rollers, means to cause the tube blank to traverse said opening, and means to pass an electric heating current through said pair of rollers and the tube joint between them.

11. In a tube-welding machine of the character described, the combination of a roller adapted to engage the tube opposite its longitudinal joint, a pair of contact rollers at right angles to said first roller adapted to engage the tube on opposite sides of said joint, overlapping discs interlocking said rollers together to prevent decrease of the size of the opening formed by the rollers, means to cause the tube blank to traverse said opening, and means to pass an electric heating current through said pair of rollers and the tube joint between them.

12. In a tube-welding machine of the character described, the combination of a roller adapted to engage the tube opposite its longitudinal joint, a pair of contact rollers at right angles to said first roller positioned to engage the tube on opposite sides of its longitudinal joint, shafts for said contact rollers, bearings for said shafts, means to maintain said shafts without play against the sides of such bearings nearest the tube, overlapping discs interlocking all of said rollers together, whereby the rollers are prevented from approaching one another and

- decreasing the opening formed by them, means to cause the tube blank to traverse said opening, and means to pass an electric heating current through said pair of rollers and the tube joint between them.
13. In a tube-forming machine of the character described, the combination of means to bend a strip of metal transversely into tubular form with a longitudinal joint at the lengthwise meeting edges of the strip, means to shape an edge of the metal at the joint to have a width of contact with the opposed edge of the metal less than the thickness of the metal, and means to cause the strip to traverse said bending and edge-shaping means.
14. In a tube-welding machine of the character described, the combination of means to bend a strip of metal transversely into tubular form with a longitudinal joint at the lengthwise meeting edges of the strip, means to shape an edge of the metal at the joint to have a width of contact with the opposed edge of metal less than the thickness of the metal, means to weld the edges of such joint together throughout the thickness of the metal, and means to cause the strip to traverse said bending, edge-shaping and welding means.
15. In a tube-welding machine of the character described, the combination of means to bend a strip of metal transversely into tubular form with a longitudinal joint at the lengthwise meeting edges of the strip, means to shape an edge of the metal at the joint to have a width of contact with the opposed edge of metal less than the thickness of the metal, means to electrically weld the edges of such joint together throughout the thickness of the metal by passing an electric heating current across the joint, and means to cause the strip to traverse said bending, edge-shaping, and welding means.
16. In a tube-forming machine of the character described, the combination of means to bend a strip of metal transversely into tubular form with a longitudinal joint at the lengthwise meeting edges of the strip, means to shape an edge of the metal at the joint to have a width of contact with the substantially central section of the opposed edge of metal less than the thickness of the metal, and means to cause the strip to traverse said bending and edge-shaping means.
17. In a tube-welding machine of the character described, the combination of means to bend a strip of metal transversely into tubular form with a longitudinal joint at the lengthwise meeting edges of the strip,
- means to shape an edge of the metal at the joint to have a width of contact with the substantially central section of the opposed edge of metal less than the thickness of the metal, means to weld the edges of such joint together throughout the thickness of the metal by heat electrically generated by a current traversing such joint, and means to cause the strip to traverse said bending, edge-shaping, and welding means.
18. In a tube-forming machine of the character described, the combination of a roller adapted to engage the longitudinal edges of a metal blank out of which the tube is made and to shape one of such edges with a plane surface substantially radially disposed with reference to the axis of the tube and shape the opposed edge of the metal with surfaces diverging from a longitudinal line substantially midway between the inner and outer surfaces of the tube, and means to feed said blank past said roller.
19. In a tube-forming machine of the character described, a concave roller having an intermediate disc portion projecting beyond the concave surface of the roller, and means to feed a metal blank past the roller with its opposite longitudinal edges bearing on and shaped by faces of said projecting part of the disc.
20. In a tube-forming machine of the character described, the combination of a plurality of concave rollers each having an intermediate disc portion projecting beyond the concave surface of the roller, and means to feed a metal blank past said rollers in series with its opposite longitudinal edges bearing on and shaped by faces of said projecting parts of the disc portions.
21. In a tube-welding machine of the character described, the combination of means to feed the tube longitudinally, a pair of contact rollers positioned to engage the tube on opposite sides of its longitudinal joint, means to pass an electric heating current through said rollers and the tube joint between them, and an insulation spacing roller between said contact rollers.
22. In a tube-welding machine of the character described, the combination of means to feed the tube longitudinally, a pair of contact rollers positioned to engage the tube on opposite sides of its longitudinal joint, means to pass an electric heating current through said rollers and the tube joint between them, and an insulation spacing roller engaging the tube joint between said contact rollers.

JOHN F. GAIL.
